NOZZLE FOR DISPENSING FLUIDS

George M. Schutter, West Newton, and Robert G. Young, Jr., Beverly, Mass., assignors to Scully Signal Company, Cambridge, Mass., a corporation of Massachusetts

Application January 14, 1953, Serial No. 23,128

Term of patent 14 years

(Cl. D52—2)

To all whom it may concern:

Be it known that we, George M. Schutter and Robert G. Young, Jr., citizens of the United States of America, residing at West Newton, Middlesex County, and Beverly, Essex County, respectively, in the Commonwealth of Massachusetts, have invented a new, original, and ornamental Design for a Nozzle for Dispensing Fluids, of which the following is a specification, reference being had to the accompanying drawings forming a part thereof.

Fig. 1 is a top plan view of a nozzle for dispensing fluids, showing our new design.

Fig. 2 is a side elevation looking from the left of Fig. 1.

Fig. 3 is a front elevation of Fig. 1.

Fig. 4 is a side elevation looking from the right of Fig. 1.

We claim:

The ornamental design for a nozzle for dispensing fluids, as shown.

GEORGE M. SCHUTTER.
ROBERT G. YOUNG, JR.
